[57] CLAIM

The ornamental design for a dart game board, substantially as shown and described.

DESCRIPTION

FIG. 1 is a front elevational view of a dart game board showing my new design;

FIG. 2 is a bottom view of the dart game, the top plan view being a mirror image thereof, a dart is shown to illustrate the environment;

FIG. 3 is a partial rear elevational view;

FIG. 4 is a second partial rear elevational view.
